L. EVANS.
BREECH LOADING CANNON.

No. 30,305.

Patented Oct. 9, 1860.

UNITED STATES PATENT OFFICE.

LEWIS EVANS, OF MORGANTOWN, VIRGINIA.

IMPROVEMENT IN BREECH-LOADING ORDNANCE.

Specification forming part of Letters Patent No. 30,305, dated October 9, 1860.

To all whom it may concern:

Be it known that I, LEWIS EVANS, of Morgantown, in the county of Monongalia and State of Virginia, have invented a new and useful Improvement in Breech-Loading Cannons; and I do hereby declare the following to be a full, clear, and exact description thereof, reference being had to the accompanying drawings, making part of this specification, in which—

Figure 1 represents a longitudinal central vertical section, Fig. 2 a plan, and Figs. 3 and 4 views of detached portions, of my breech-loading gun.

Similar letters of reference represent like parts in each of the several figures.

The nature of my invention consists in first locking the breech-piece in the breech end of the barrel by means of a hinged lock-bar passing through a slot in the breech-piece and corresponding slots in the breech end of the barrel; second, operating the hammer by means of a hinged dog and crank-shaft; third, adjusting the breech-piece in line with the barrel by means of toothed brackets moving in vertical ways; fourth, the combination of the breech-piece with a sliding standard, spring-catch, pin, incline, and rack-gear, for the purpose of moving the breech-piece into the breech end of the barrel when required.

To enable others skilled in the art to make and use my invention, I will proceed to describe its construction and operation.

The gun A is pivoted to a frame, B, supported by a shaft, C, and carriage-wheels D D, in the usual manner. The breech end of the gun is open and enlarged, so as to receive a separate breech-piece, F. The bore of the breech-piece is lined with a tube of thin metal. The rim of this tube A' projects beyond the end of the breech-piece and fits into a corresponding recess in the bore of the gun. On firing the gun the rim of the tube A' expands and fills the said rim tightly, so as to prevent all windage. When the breech-piece is in the breech end of the gun, a slot in the breech-piece corresponds with two slots in the breech end of the gun. By inserting the bar J through said slot G the breech-piece is firmly locked or wedged into the breech end of the gun. To move the bar J up for the purpose of locking the breech-piece, as described, it is hinged

to the forward end of the lever H. The lock-bar J will be thrown up in the manner and for the purpose set forth. The lock-bar is hinged to the lever in order that it can freely adapt itself to every motion of the gun on its pivots. Each breech-piece is provided with a number of short projections, Q, near its rear end, which take into corresponding notches in the breech end of the barrel, and serve to adjust the breech-piece while being inserted, so that the slot in the breech-piece will be exactly in line with the slot G in the barrel, ready for the insertion of the lock-bar.

A number of breech-pieces, F, are arranged in radial lines around the center of a disk, y. A bolt, K', passes through a hole in the center of the disk y, and through holes in the rear end of the gun-carriage, and through a hole in the carriage supported on wheels N' N', thus connecting together the gun-carriage and the carriage supporting the disk y. On turning the disk around its center-bolt, the breech-pieces, which have previously been charged, are successively brought into line with the gun-barrel. Each breech-piece is held near its mouth between two brackets, L L, which slide in vertical ways projecting from the disk y. The brackets can be adjusted higher or lower, so as to raise or depress the mouth of the breech-piece, in order to bring it in line with the breech end of the gun, by raising or lowering the brackets in their ways and confining them in the desired position by means of the rack-teeth on the back of each bracket and a stationary pin, N, extending across each of the vertical ways or slots in the standards. The rear end of each breech-piece is provided with a short neck and knob, S. This neck is hung into a forked standard, R, which is free to slide forward and backward in a radial slot, Z, in the disk y parallel with the axis of the breech-piece. These standards R are each provided with a projection, P, near its rear edge. When the breech-piece is at the inner end of slot Z, a spring-catch pivoted to the disk y takes hold of projection P, so as to prevent the breech-piece from moving forward; but when the disk y is turned so as to bring the breech-piece in line with the gun-barrel, a pin, Q, inserted through the standard immediately below the catch and through slot Z, is raised by coming in contact with the

inclined surface of a tongue, T, hereinafter described. While the pin moves up this inclined surface, its upper end raises the catch O above the projection P, and the standard R is now free to be moved forward in the slot Z for the purpose of inserting the breech-piece into the breech end of the gun. The standard is moved forward and backward in the slot Z in the following manner: The standard is made with a shank, which extends below and through the slot Z. As the disk is turned on its center-bolt so as to bring the breech-piece in line with the gun-barrel, said shank enters a slot between two tongues, T U, projecting from a rail, V. This rail rests in ways X in the carriage-frame supporting the disk y, and can be moved forward or backward by means of rack-teeth in the upper surface of said rail, and a cog-wheel, W, gearing into the rack-teeth, moves the rail and, by means of the tongue T U, between which the standard-shank is held, the standard R and breech-piece forward or backward, so as to insert the breech-piece into or withdrawing it from the breech end of the gun-barrel. After the charge has been fired and the breech-piece withdrawn, the disk Y is turned so as to bring the next breech-piece in line with the barrel. As the breech-piece which has just been fired and withdrawn is removed, together with the disk Y, the pin Q slips off the inclined surface of tongue T and allows the catch O again to take hold of the projection P.

The hammer F slides through an inclined hole in the breech end of the barrel. When the breech-piece is inserted, its nipple J is in line with the hammer. A little projection, G, on the face of the hammer prevents the hammer from protruding too far below the inner end of the hammer-hole, and thus being in the way of the breech-piece when inserted. The upper end of the hammer is formed into a hook, H'. In front of the hammer a small crank-shaft, B, is held in bearings projecting from the gun-barrel. A dog, E', made in two parts, hinged together at C', is attached at one

end to the crank-shaft B. On giving the crank-shaft part of a turn, so as to depress the edge of the dog and withdraw it from the hammer, and then turning the shaft back, the edge of the dog enters underneath the hook H'. By continuing to turn the shaft in this direction the dog raises the hammer, and by the time the dog slips from underneath the projection H' the hammer is thrown down by the action of the spring I', which bears against the upper end of the hammer, and is thus made to strike the nipple J with sufficient force to explode the cap and discharge the gun.

Pointed bars or anchors E are hinged to the gun-carriage-shaft extending backward. When the gun is being moved about, the rear ends of the anchors are hung into hooks O', secured to the gun-carriage; but when the gun is in position ready for firing, the rear ends of the anchors are dropped onto the ground, so as to bear against the ground and prevent the recoil of the gun while being fired.

What I claim as my invention, and desire to secure by Letters Patent, is—

1. Locking the breech-piece F in the breech end of the barrel A by means of a hinged lock-bar, J, passing through a slot in the breech-piece and corresponding slot in the breech end of the barrel, as and for the purposes herein described.

2. Operating the hammer F' by means of a hinged dog, E', and crank-shaft B', as and for the purposes herein described.

3. Adjusting the breech-piece in line with the barrel by means of toothed brackets L, moving in vertical ways, as and for the purposes herein described.

4. The combination of the breech-piece F with a sliding standard, R, spring-catch O, pin Q, incline T, and rack-gear W V, for the purposes herein described.

LEWIS EVANS.
